UNITED STATES PATENT OFFICE.

EDWARD L. HOPKINS, OF COLUMBUS, OHIO, ASSIGNOR TO THE JEFFREY MANUFACTURING COMPANY, OF COLUMBUS, OHIO, A CORPORATION OF OHIO.

BRAKE FOR MINING-MACHINE TRUCKS.

1,218,402.

Specification of Letters Patent.

Patented Mar. 6, 1917.

Application filed June 30, 1915. Serial No. 37,331.

To all whom it may concern:

Be it known that I, EDWARD L. HOPKINS, a citizen of the United States, residing at Columbus, in the county of Franklin and State of Ohio, have invented certain new and useful Improvements in Brakes for Mining-Machine Trucks, of which the following is a specification, reference being had therein to the accompanying drawing.

10 This invention relates to a brake mechanism peculiarly designed for use on the low trucks which are used in coal mines for transporting mining or kerf cutting machines from one part of a mine to another.

15 As is well known, all machinery used in coal mines must be arranged as compactly as possible, as the available open room or space formed in excavating the coal is restricted both vertically and horizontally, 20 and the machines that are to be manipulated in these spaces must have their parts all brought as closely together as possible.

The coal undercutting machines have, in later years, come to be very heavy and more 25 or less cumbersome. After performing their special work in one part of a mine, they must be loaded on trucks with low platforms on small wheels and taken to other parts, the trucks being fitted to the tracks that are 30 laid in narrow entries and the rooms with low roofs, and being specially built for the transportation of these heavy machines. They cannot have more than a few parts, and must be without projections.

35 The mining machines are dragged or pushed from the truck, and later, are dragged back upon them, and during these movements require application of bars and tools at their ends and along their sides.

40 With all of these adverse conditions it has been found practically impossible to provide these trucks with any of the ordinary means for braking and controlling the track wheels and the axles, as they are always 45 characterized by the presence of large rotary devices, such as brake drums or cumbersome projecting brake shoe mechanisms and levers extending upward or outward to operate such devices. Yet it has long been

50 known to be a desideratum to have such brake control of the vehicle when moving as the trucks are called upon to go up and down grades, sometimes quite severe, and when loaded with the heavy cumbersome 55 mining machine (particularly when the

track wheels are power driven) the trucks often get beyond control of the operative and accidents consequently happen.

The object of the present invention is to provide one of these low, specially constructed, mining machine trucks with a brake device which will have no metallic or wooden parts of any of the ordinary sorts that are subject to breakage; can be applied to one of the low axles in such way 60 that there will be no vertical or horizontal projections; will, as an entirety, be practically entirely out of the way when the mining machine is being loaded upon, or removed from, the truck; will comprise parts 65 that are inexpensive and available at all ordinary places; will not require work in the shop or skilled labor for adjusting it, or any specially made parts to be replaced in case of the wearing out of the one in use, 70 but can be immediately fixed properly at any place in the mine by any unskilled operative; and yet will be effective in controlling the movements of the truck and its heavy load under all the ordinary circumstances in the mine.

Figure 1 is a plan view of a mining machine truck equipped with my brake mechanism;

Fig. 2 is a side elevation of the truck, 85 some of the parts being broken away, and showing conventionally, by dotted lines, the position of a mining machine when in place thereon;

Fig. 3 is a rear elevation of some of the 90 parts.

While the parts constituting more particularly the present invention may be applied to trucks of modified form, I have, in the drawings, illustrated one which is 95 typical of those now universally employed in coal mines for the transporting of mining machines.

It is constructed with a frame having longitudinal angle bars 1 joined together by 100 the cross bars or girts, as at 2 and 3. It has a forwardly extending skid frame 4 to guide and support the cutting machine when it is being brought to, or taken from, the truck. 5 are the axle boxes fastened to the bars 1, 105 and in these are journaled the axles 6 and 7. 8, 8 are the small flanged truck wheels rigidly fastened to the axles 6 and 7, and fitted to the rails 9 of the tracks in the mine entries and rooms.

The axles 6 and 7 are elevated but a few inches above the track, and the bottom of the truck body is disposed in low planes as close to the axle as it can be brought, for it is a matter of considerable labor to get the mining machine (some weighing several thousand pounds) up, even to a low horizontal plane, on the truck, and in many places the top of the mining machine is close to the roof when loaded.

When the cutting machine is to be loaded it must be moved over the surface of the ground by bars or tools, in the hands of the operators, until it is approximately aligned with the truck. Then, to assist the operatives with their bars, in bringing it up, provision is made of a chain 22 secured to a spool or drum 20 and having a hook which can be loosely attached to the rear end of the cutting machine. The drum 20 is rotated by the hand ratchet lever 21, and power applied longitudinally of the truck to draw the cutting machine to place. The latter has component parts or attachments along its sides which overhang the side rails 1 of the truck and do not allow any vertical projections to be present on the latter. And it is frequently necessary to apply, along the side of the truck or the machine, bars or tools, to assist in bringing the machine to proper position. The spool or drum 20 is mounted on a shaft 16 which is in turn mounted (in bearings 17, 18) on a low horizontal line, as near the bottom as possible, and at the rear end of the truck. The motor 28 of the mining machine, through chain 26, sprocket wheels 27 and 19, chain 14, and sprockets 15 and 13, transmits power to the axle 6, and the latter, through chain 12 and sprockets 10 and 11, drives axle 7.

The power transmitting devices are arranged compactly and as close as possible to the sides of the truck to avoid the presence of lateral projections, for the passageways in many parts of the mines (as in the necks to the rooms and the narrow entries) are horizontally restricted by the walls of coal.

The motor 28 is disconnected by clutch 31 from the cutting apparatus and connected to the aforesaid truck driving devices.

The parts thus far described have no provision for controlling the truck wheels or axle except by switching the motor on or off. And it will be seen that, as above described, none of the ordinary brake devices can be applied, for the numerous mechanical parts in such brakes, as levers, links, brake shoes, and the like, are prohibited.

My braking and controlling device consists of a rope having the strands 24 and 25, the intermediate coils 23 (of a suitable number) wrapped around one of the axles 6, and the end parts 24^a, 25^a secured to a stationary holder on the truck. The strands

24, 25 pass over the spool or drum 20 and their ends 24^a, 25^a are passed through slots or apertures in the cross girt or bar 29 and tied or knotted. The total length of the rope is such that there will normally be a small amount of slack. The slack can be predetermined so that neither part of the rope will drag upon the ground, but both parts can droop sufficiently to permit the rear end of the cutting machine to be brought well back toward the rear end of the truck without pressing against the rope.

As will be seen from the drawings, the truck is constructed to have an opening or passage behind, and relatively close to, one of the axles, and also behind the rear vertical lines of the mining machine; and the slack portions of the rope are carried upward through this passageway, and then over the devices at 20, the latter serving as a holder to sustain the end portions of the rope and bring them where either, independently of the other, can be grasped by the operator's hand.

When the operator desires to exert a braking effort on the axles and track wheels, he grasps one of the strands 24, 25 at a point above or in front of the spools 20 and applies sufficient tension to cause the coils 23 to grip the axle and retard rotation. He grasps the end of the rope 25 when he desires to brake or check the car, if it is moving toward the right (as shown in the drawings), for the near end of the rope coil is then tending to unwind; and, vice versa, he grasps the rope 24 if he desires to check the car when moving toward the left. In either case the cross bar 29 of the truck frame serves as the stationary abutment for the braking effort.

The weight of the rope on the axle is practically nothing, and consequently there will be but little wear on the axle in turning loose in the coil. But should wear occur or should the rope break, or should it be found necessary to increase the number of coils, it is a simple matter for the operator to effect repair, or substitute a new brake, or lengthen the coil part, even though this is to be done in the depths of the mine, and can be accomplished without the necessity of taking the truck to the machine shop, or any demand for skilled labor. Even though the rope should, at the sagging part, contact with the ground or with the track ties, it is immaterial, as no positive obstructions are presented, as impediments or cause of breakage.

What I claim is:

The herein-described brake for a mining machine truck mounted upon relatively low axles and constructed to have a vertically open space behind one of said axles and behind the mining machine when in position, comprising a flexible rope having both ends

separately and detachably but rigidly secured to a holder rigidly stationary with the truck frame, said rope being coiled around the axle and having both end portions normally slack between the fixed fastening points and the axle, and a sustaining device for the slack portions of the rope which cause it to extend upward through the said opening where it is exposed to have either 5 end independently of the other manually 10

grasped to cause tension to be exerted on the fixed frame attachment point by the coils on the axle.

In testimony whereof, I affix my signature, in presence of two witnesses.

EDWARD L. HOPKINS.
